UNITED STATES PATENT OFFICE

2,411,804

RADIO KALEIDOSCOPIC PROJECTOR

Leonard Z. Plebanek, Chicago, Ill.

Application January 8, 1944, Serial No. 517,596

16 Claims. (Cl. 88—24)

1

This invention relates to a kaleidoscopic projector and concerns itself primarily with means for projecting a constantly varying or changing pattern on a screen and it is an object of this invention to provide such an apparatus which is responsive to sound air waves preferably emitted by a radio loud speaker which will cause a constant variation in the projected kaleidoscopic pattern or design on a screen and which will vary the color scheme by means responsive to the pitch of sound air waves which may result from a radio loud speaker especially during a musical program; during such musical program, the various patterns will substantially follow the tempo or rhythm of the music.

During the use of such an apparatus, many artistic and beautiful patterns may be formed or created and in the event that it is desired to obtain a copy or impression of such pattern or design, this may be done by shutting off the radio or source of the sound air waves. The light will, of course be left on while the copy or impression is taken.

With these and other objects in view which will become apparent as the description proceeds, this invention comprises the novel structure and combinations of parts hereinafter described and more particularly pointed out and defined in the appended claims.

In the accompanying drawings which illustrate a preferred form of this invention and in which similar reference numerals refer to similar features in the different views;

Fig. 1 is a longitudinal sectional view of an apparatus involving this invention.

Fig. 2 is an enlarged sectional view taken substantially upon the line 2—2 of Fig. 1.

Fig. 3 is a top plan view of the apparatus with the casing shown in section.

Fig. 4 is a sectional view taken upon the line 4—4 of Fig. 1 looking in the direction of the arrows.

Fig. 5 is an enlarged sectional view taken upon the line 5—5 of Fig. 1 looking in the direction of the arrows.

Figs. 6 and 7 are views similar to Fig. 5 showing sections of the other light units.

Fig. 8 is an enlarged sectional view taken upon the line 8—8 of Fig. 1.

Fig. 9 is a sectional view taken substantially upon the line 9—9 of Fig. 1 looking in the direction of the arrows and showing parts in elevation.

Fig. 10 is an elevational view of the screen showing one form of an image and taken upon the line 10—10 of Fig. 3.

2

In referring to the drawings which illustrate an embodiment of this invention, there is shown a casing 11 which is closed except as to its rear end which may be open or provided with an aperture for receiving the sound air waves from a radio loud speaker. The sound air waves entering the casing are adapted to operate five diaphragms, 13, 14, 15, 16 and 28 (Figs. 1 and 3). The diaphragms 13 and 28 are designed to be operated always during the use of the apparatus while the diaphragms 14, 15 and 16 may at times not be all in operation depending upon the pitch of the sound air waves. In other words, they are designed to respond to the pitch of the sound air waves; thus one may respond to a low pitch, another to a medium pitch and the other to a high pitch. Then there may be partial response from one or more and complete response from others. This variation in responsive action produces a mixture of colors that varies the color of the pattern or design as will later more fully appear.

The diaphragm 13 (Figs. 1 and 9) is connected to a bracket frame 17 having a base portion 18 resting upon the bottom of the casing 11. The diaphragm 13 is connected with a link 19 which in turn is connected to an arm or lever 20 pivotally mounted upon a bracket 21 rising from the base 18 and carrying a pawl 22 on its upper end for operating a ratchet wheel 23 which is held 30 from reverse rotation by a holding pawl 24. The ratchet wheel 23 is fast on a stub shaft 25 mounted in ball bearings 26 housed in the bracket frame 17. The upper end of the shaft 25 carries a spider 27 which supports a ring 27a that carries 35 a dished diaphragm 28 previously referred to and which is in the form of a tray. The tray contains objects 29, 30, 31, 32, 33, and 34 of various shapes and designs which may be made of light material such as paper, tinsel or Celluloid.

40 Rotation of the stub shaft 25 step by step by the ratchet wheel 23 will rotate the tray 28 and change the positions of the objects therein with respect to the rays of light that illuminate the objects as will later appear, while the vibrations 45 imparted to the tray by the sound air waves will move the objects 29 to 34 relative to each other so that a continually changing or varying pattern or design with respect to the projected image will be produced.

50 Above the tray 28, there is a hood 36 which is supported over the tray by arms 38 which may extend from the bracket 17. The hood 36 is provided with an opening 39 in its top for the exit of reflected rays from the objects in the tray, 55 which rays pass thru the open top of the tray

and the open bottom of the hood. Above the opening 39 in the hood, the hood is provided with a neck portion 36a in which are secured convex lenses 44a in spaced relation that tend to brighten and render more definite the pattern that is projected.

Rays of differently colored light are adapted to be thrown upon the objects 29 to 34 from the light units 41, 42, and 43, each of which carries a light bulb 40 at its top. These units are spaced 120 degrees apart and are at an elevation for projecting light rays upon the objects. Each unit is of similar construction; that is they are alike except as otherwise noted so a description of one will generally apply to the others. A spherical light reflecting member 41a is positioned under the cover 41b of each light casing. Light rays will be reflected from the reflectors 41a in a downward direction and many will pass thru the condenser lenses 44-44 which are mounted in cylindrical neck portions 41c upon the lower ends of the light casings. These condenser lenses are plano-convex and are mounted in spaced relation and serve to illuminate strongly the objects in the tray.

The neck portions 41c of the light casings are provided with slots 45 between the lenses 44-44. The slot in the casing 41 is adapted for receiving a red film disk 46; the slot in the casing 42 is designed to receive a yellow film disk 47; and the slot in the casing 43 is adapted to receive a blue film disk 48. Each color film 46, 47 and 48 is carried by a similar lever 49 which is pivoted at its upper end in an arm 50 extending from the frame bracket 17. Each lever 49 has a foot 49a to which the color films are attached in any suitable manner. Each lever 49 is connected by a strut or arm 51 with its respective diaphragm 14, 15 or 16 of the artificial light units.

The diaphragms 14, 15 and 16 should be of different strength, yieldability or size so that one will respond to sound air waves of low pitch; another to sound air waves of medium pitch and the other to sound air waves of high pitch. As these diaphragms are flexed by sound air waves, the levers 49 will be actuated in accordance with the pitch of such waves to move their respective films into the paths of the light rays passing thru the condenser lenses, which rays will illuminate strongly the objects 29 to 34 in the tray 28. The light units may be secured in position at the most advantageous angle by welding or in any other suitable manner.

From the strongly illuminated objects in tray 28 which have reflecting surfaces, rays of light will be reflected upwardly thru the aperture 39 in the hood 36 and pass thru the double convex lenses 36a which will strengthen the illumination cast upon an inclined mirror 52 suitably supported from which rays of light will be reflected upon the interior surface of a V-shaped light reflector 53 which has an interior angle of sixty degrees which creates a six sided kaleidoscopic design. The interior surfaces of the reflector are preferably highly polished.

Rays of light will be reflected from the reflector 53 (Figs. 1 and 4) and pass thru a pair of spaced double convex lenses 54-54 located in the neck of flaring screen support 56 having a circular transparent screen 57 fixed in its outer end. This screen may be provided with an inner sand blasted surface 58 to receive the image projected by the rays of the objects 29 to 34 in the tray 28; the lenses 54 serving to brighten the image and rendering the same more definite.

The image projected upon the screen 57 may be of the design or pattern 57 shown in Fig. 10. But this design or pattern will constantly change or be varied due to the shimmering or movements of the objects 29 to 34 in the tray 28 caused by the vibrations imparted to such tray by the sound air waves emitted by the radio loud speaker 12. At the same time, the colors of the image projected will be changed in accordance with the pitch of the sound waves acting upon the diaphragms 14, 15 and 16. This change of pitch will especially be pronounced during a musical program on the radio when high, low and intermediate notes are uttered.

Thus thru a changing color scheme and the vibratory movement of the objects forming the basis of the projected image, the patterns or designs of the image are constantly changed in an interesting and fascinating manner.

The apparatus is readily adapted to home use by positioning the same with the open end toward a radio loud speaker. The lights 40 should, of course, be turned on when it is desired to use the apparatus. Thereafter the apparatus functions automatically; the sound air waves operating the different diaphragms for effecting changes in color, design or pattern of the image projected while the reflected light rays project the different patterns or designs.

In practice, it may be desirable to place the apparatus in a radio cabinet or the like or it can be positioned in any convenient location adjacent thereto. The screen upon which the kaleidoscopic pattern is projected will, of course, be located in a readily observable place. After a kaleidoscopic pattern has been projected, the action of the sound waves which cause the objects to move and change their locations and cause the reflected light to change the color of the light reflected from the objects will be instrumental in causing a continual change in the projected kaleidoscopic design that may be very fascinating to observe.

On account of the ease with which the objects 29 to 34 may be changed for different objects of other shapes, designs and sizes, it becomes possible to further increase the number of kaleidoscopic designs and in this way the apparatus may serve as a creator of new patterns or designs.

I am aware that many changes may be made and various details of construction may be varied without departing from the principles of this invention so I do not propose limiting the patent that may be granted thereon otherwise than necessitated by the appended claims.

I claim as my invention:

1. In a kaleidoscope, a screen, means for projecting a constantly changing pattern on said screen comprising a diaphragmatic tray, movable objects of different size and design in said tray, means including a diaphragm for rotating said tray, a plurality of light projecting units surrounding said tray at an elevation for casting light rays upon said objects for reflection therefrom, a differently colored film disk associated with each unit and adapted for movement into and out of the path of the rays of its unit, a diaphragm connected to each unit disk, each of said last mentioned diaphragms being responsive to different pitch of sound air waves emitted from a radio loud speaker.

2. In an apparatus of the class described, a screen, means for projecting a constantly changing pattern upon said screen comprising a plurality of light reflecting objects of different de-

sign, a diaphragmatic tray for supporting said objects, a shaft connected to said tray, a ratchet wheel carried by said shaft, a pivoted lever having a pawl engaging said ratchet wheel and a diaphragm responsive to sound air waves from a radio loud speaker having a connection with said lever.

3. In an apparatus of the class described, a screen, means for projecting a constantly changing pattern upon said screen comprising a plurality of light reflecting objects of different shapes, a diaphragmatic tray for supporting said objects, a shaft connected to said tray and means for intermittently rotating said shaft and tray comprising a diaphragm responsive to sound air waves from a radio loud speaker and an operative driving connection between said shaft and said diaphragm.

4. In a kaleidoscope, a screen, light reflecting means for projecting a constantly changing pattern upon said screen comprising light reflecting objects of different designs, means for moving said objects, spaced means for casting pencils of light rays upon said objects and means for changing the color of said light rays comprising a plurality of differently colored disks, one associated with each pencil of light rays, a diaphragm for each disk, an operative connection between each disk and its diaphragm, each diaphragm being responsive to a different pitch of sound air waves and a source of sound air waves of different pitch for operating said diaphragms.

5. In a kaleidoscope, a screen, a plurality of light reflecting members, light reflecting objects of different designs for receiving the rays of light from said members, means for moving said objects, a differently colored film disk movable into and out of the pencil of light rays emitted by each member, diaphragms responsive to different pitches of sound air waves, each having an operative connection with a disk and a source of sound air waves of different pitch for impinging against said diaphragms.

6. In a kaleidoscope, a screen, light reflecting means for projecting a constantly changing pattern upon said screen comprising light reflecting objects of different designs, means for moving said objects, spaced light reflecting members for directing light rays upon said objects, a separate film disk associated with the light rays from each member, a device connected to each film disk, each device being responsive to a different pitch of sound air waves, and a source of sound air waves susceptible of different pitch for operating said devices.

7. In a kaleidoscope, a screen, means for projecting a constantly changing pattern upon said screen comprising a plurality of light reflecting objects of different designs, a diaphragmatic tray for supporting said objects, means including a shaft connected to said tray for providing an operating connection, a diaphragm responsive to sound air waves, operating means between said diaphragm and shaft for intermittently rotating the latter and a source of sound air waves for vibrating said diaphragms for agitating the objects in said tray diaphragm and causing rotation of the same.

8. In a kaleidoscopic apparatus for projecting a constantly changing pattern upon a screen including a plurality of movable light reflecting objects, light ray reflecting units for casting rays upon said movable objects, a plurality of differently colored film discs adapted for projection into the path of said rays, means for supporting

said film discs for movement into and out of the path of said rays, a source of sound air waves of different pitch and members having different pitch responsiveness, each connected to a disc supporting means and being responsive to said source of sound air waves.

9. In a kaleidoscopic apparatus for projecting a constantly changing pattern upon a screen including a plurality of movable objects of different shapes having light reflecting surfaces, a plurality of light projecting devices for directing light rays upon said objects and having guide ways, a differently colored film disc positioned in each guide way, means for supporting each disc for movement into and out of the light rays emerging from its device, a source of air waves of different pitch, and members having different degrees of responsiveness, one connected with each disc supporting means and responsive to said source of air waves.

10. In a kaleidoscopic apparatus for projecting a continuously changing pattern upon a screen, a diaphragmatic tray, movable objects having light reflecting surfaces in said tray, means between said tray and screen for projecting the pattern of said objects upon said screen, a plurality of light reflecting units at an elevation for projecting light rays upon said objects and having guideways, a differently colored film disc associated with each unit and positioned in the guideway thereof, means for supporting and moving each disc into and out of the light rays of its unit comprising diaphragms of differing responsiveness, each diaphragm having a connection with a film disc support, and a source of sound air waves of different pitch for vibrating said diaphragm and said tray.

11. In a kaleidoscopic apparatus for projecting a constantly changing pattern upon a screen including a diaphragmatic tray having light reflecting objects therein, a plurality of spaced light reflecting units for directing pencils of rays upon said objects, means for supporting a differently colored film disc adjacent each pencil of light rays, diaphragms of different responsiveness, respectively connected to said disc supporting means and responsive to different sound waves from a radio loud speaker or the like.

12. In a kaleidoscope comprising a screen, and a rotary and vibratory tray containing light reflecting objects with means between said screen and tray for projecting the pattern reflected from said objects upon said screen, a plurality of spaced light reflecting units surrounding said tray for reflecting light rays upon said objects, each unit comprising a conical housing with a cylindrical neck projecting toward said tray, spaced condenser lens in said neck the neck of each unit having a slot between its lenses, a movable support mounted adjacent each unit, a differently colored film disc carried by each support and adapted for movement into and out of the slot in the adjacent housing, a plurality of diaphragms of different sound pitch responsiveness, one connected to each support and a source of varying pitch of sound air waves for operating said diaphragms and tray.

13. In a kaleidoscope comprising a screen and a rotary and vibratory tray containing light reflecting objects with means between said screen and objects for projecting the pattern reflected from said objects upon said screen, a plurality of spaced light reflecting units surrounding said tray, each unit comprising a conical housing with a neck portion directed toward said tray, each

neck portion having a slot, a differently colored film disc adapted for movement into each slot and into the rays passing through the neck portion thereof, a movable support for each film disc, diaphragms of different sound pitch responsiveness, one connected to each movable support and a source of varying pitch of sound air waves for operating said diaphragms.

14. In a kaleidoscope comprising a screen and a rotary and vibratory tray containing light reflecting objects therein with means between said screen and objects for projecting the pattern reflected from said objects upon said screen, a plurality of spaced light reflecting units surrounding said tray for reflecting pencils of light rays upon said objects, a movable support adjacent the path of each pencil of ray, a differently colored film disc carried by each movable support for movement into the adjacent pencil of light rays, diaphragms of different sound pitch responsiveness, one connected to each support and a source of varying pitch sound air waves for operating said diaphragms.

15. In a kaleidoscopic apparatus, a screen, a vibratory tray, movable light reflecting objects in said tray, means between said tray and screen for reflecting the pattern from said objects upon said screen, a plurality of light ray reflecting units surrounding said tray for casting pencils of light rays upon said objects, and each having a

10

guide way, a differently colored film disc in each guide way, a movable support for each film disc, diaphragms of different sound pitch responsiveness, one connected to each support, and a source of varying sound pitch air waves for operating said diaphragms and tray.

16. In a kaleidoscopic apparatus, a screen, means for projecting a constantly changing pattern upon said screen comprising a pair of spaced condenser lenses in cooperative relation with said screen, a reflector for directing light rays into said lenses, a mirror for reflecting light upon said reflector, a tray, movable objects having light reflecting surfaces in said tray, means for rotating and vibrating said tray, a light ray conducting cylinder extending above said tray, spaced lenses in said cylinder for directing light rays upon said mirror, a plurality of spaced light projecting units surrounding said tray at an elevation for reflecting light rays upon said objects, each unit having a pair of spaced condenser lenses, movable supports adjacent each unit, a differently colored film disc carried by each support and movable between the condenser lenses into and out of its unit, diaphragms responsive to different pitches of sound air waves, one connected to each support and a source of sound air waves for operating said diaphragms.

LEONARD Z. PLEBANEK.
